UNITED STATES PATENT OFFICE.

CARL H. ZWERMANN, OF KALAMAZOO, MICHIGAN.

FLOAT.

964,729.

Specification of Letters Patent. Patented July 19, 1910.

Application filed January 31, 1910. Serial No. 541,083.

To all whom it may concern:

Be it known that I, CARL H. ZWERMANN, a citizen of the United States, residing at Kalamazoo, Michigan, have invented certain new and useful Improvements in Floats, of which the following is a specification.

This invention relates to improvements in floats.

The main objects of my invention are: 10 First, to provide an improved float which is economical to produce and is effective and very durable. Second, to provide an improved float which is especially adapted to be made of metal and effectively coated with 15 enamel inside and out, though it may be easily formed of glass or porcelain, or of some corrosion resisting metal.

Further objects, and objects relating to structural details, will definitely appear from 20 the detailed description to follow.

I accomplish the objects of my invention by the devices and means described in the following specification.

The structures described constitute one effective embodiment of my invention.

Other embodiments can be readily devised by those skilled in the art.

The invention is clearly defined and pointed out in the claims.

30 Structures constituting effective and preferred embodiments of the features of my invention are clearly illustrated in the accompanying drawing, forming a part of this specification, in which:

35 Figure 1 is a vertical section through a tank structure with a float embodying the features of my invention shown in operative position; Fig. 2 is a vertical central section through one of my improved floats; Fig. 3 40 is a section corresponding to Fig. 2, showing a modified form of connection to the arm; Fig. 4 is a detail section of still another form of arm connection, taken on line 4-4 of Fig. 5, and Fig. 5 is a transverse 45 plan section on line 5-5 of Fig. 4.

In the drawings, similar reference numerals refer to similar parts throughout the several views.

Referring to the drawings, 1 represents 50 a tank, such as a water closet tank, and 2 the outer wall or casing thereof. A supply pipe 3 is arranged through the bottom of the tank and projects upwardly therein. An inlet valve 4, details of which are not here 55 shown, is provided.

My improved float comprises a shell 5, cy-

lindrical in form and having hemispherical ends 6 and 7. The lower rounded end 7 has a central hole or opening therethrough, and produces a structure in which air is effectively confined and from which water is excluded, except as the contained air is compressed by the pressure of the water.

The arm 9 in the structure illustrated is fulcrumed at 10 to the bracket 11 on the inlet 65 pipe. This arm is connected to the valve stem 12 and controls the same.

In the structure shown in Figs. 1 and 2, the arm is provided with an upturned end 13 at its outer end, which is arranged axially 70 of the float shell and threaded into the internal nipple 14 in the upper end thereof. This forms a rigid connection for the arm to the float, and keeps the float in an upright position.

75 In the modified construction shown in Fig. 3, the arm 9 is threaded into a nipple 15 arranged in the side of the float below the center thereof, so there is no tendency for the float to unscrew.

80 In the modifications in Figs. 4 and 5, the arm 9 is secured to a nipple 15 on a cross bar 17. There are thus two apertures, 16 and 16, in the bottom of the float.

85 In operation, the opening in the float is sealed by the water in the tank, thereby confining the air in the float and rendering it buoyant. By rounding the lower end of the float and providing a restricted opening 8 therefor, but little water is required to seal 90 the float, and it is not likely to be unsealed by the changing of the angle of the float, as it is carried upward in the arc of a circle on the connecting rod.

95 It is desired to comment that any means which will retain the float of the character I have described substantially upright with the aperture downward, so that the air will be effectively confined therein, subject to the pressure of the water upward through the 100 aperture, will secure the benefits of my improved structure, when properly connected by any means.

This float is very economical to manufacture and when made of sheet metal and 105 enameled, it is easily completely coated inside and out, and consequently can be made of iron and not be subject to corrosion, the aperture in the bottom making the float especially adapted to this end. This form, 110 however, lends itself to glass floats and to copper floats, although, as I have stated, it

was especially designed by me for use in making a float of enameled metal. Hollow sealed glass floats have been attempted without complete success.

5 While the float is especially effective with the hemispherical bottom with the central aperture, and I desire to claim that form specifically, I will state that a float which is arranged with a downwardly-opening aperture with a suitable chamber for confining the air will be effective and practical and I desire to claim the same broadly.

Having thus described my invention, what I claim as new and desire to secure by Letters Patent is:

1. A float consisting of a metal shell, enameled outside and inside and having a rounded bottom with a central opening to confine air therein; and a lever arm having 10 an upwardly-turned end disposed axially of said shell through said opening and secured rigidly to the interior.

2. A float consisting of a metal shell, enameled outside and inside and having a rounded bottom, with a central opening to 25 confine air therein; and means for maintaining the float substantially upright.

3. A float consisting of a metal shell, enameled outside and inside and having an open bottom to confine air therein; and 30 means for maintaining the float substantially upright.

4. A float consisting of a shell having a rounded bottom, with a central opening to confine air therein; and means for maintaining the float substantially upright.

In witness whereof, I have hereunto set my hand and seal in the presence of two witnesses.

CARL H. ZWERMANN. [L.S.]
